UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN-CONTROL SYSTEM.

Application filed May 15, 1919, Serial No. 297,343. Renewed August 20, 1924.

To all whom it may concern:

Be it known that I, WINTHROP K. HOWE, a citizen of the United States, and resident of the city of Rochester, in the county of 5 Monroe and State of New York, have invented a new and useful Automatic Train-Control System, of which the following is a specification.

This invention relates to automatic train 10 control systems for railroads, and more particularly to an arrangement of trackway circuits for economizing the energy demanded from the track batteries, or the like, used in connection with the system.

15 In some types of automatic train control systems, it is necessary to supply current under clear traffic conditions to the trackway elements of the impulse transmitting means used to establish communication from 20 the track to the train. For example, in systems utilizing electromagnets, or permanent magnets with demagnetizing or neutralizing coils, as the impulse transmitting element along the track, it is necessary to 25 supply current to these magnets whenever it is desired to permit a train to pass without receiving a cautionary or stopping impulse. In some instances, the amount of current required to maintain the trackway elements in 30 the proceed condition is so great that the primary batteries, ordinarily used in block signaling systems, are inadequate for this purpose, on account of the heavy current demand extending over long periods.

35 One of the principal objects of this invention is to devise an arrangement and construction of trackway circuits for automatic train control systems, in which the energy required for the trackway elements is economized by cutting in the current supply only upon the approach of a train, or during its 40 passage, so that the demand for current is temporary and exists only when such current is required.

45 Other specific objects and features of the invention will appear hereinafter as the description progresses, and the novel features will be pointed out in the appended claims.

50 For the purpose of disclosing my invention, I have illustrated in the accompanying drawing, in a simplified and diagrammatic way, some of the various forms which the trackway circuits embodying my invention 55 may take.

In describing the various modifications reference will be made to the accompanying drawing, in which the reference characters designate corresponding parts in the several views, and in which:

50 Figures 1, 2 and 3 illustrate different modifications of a construction and arrangement of trackway circuits embodying the features of my invention; and Fig. 4 is a 60 diagrammatic view showing one form of a trackway element, together with the cooperating car carried element and associated control devices, which may be used in connection with the trackway circuits illustrated in Figs. 1 to 3.

65 In the accompanying drawings, I have illustrated my system applied to only two blocks; but it will be readily recognized by those skilled in the art that in practice the same scheme and arrangement of parts 70 would be associated with the several blocks to constitute a complete system as required, and with such variations as special conditions may demand. The various devices commonly used in ordinary block signaling 75 are shown in a conventional manner; and since the various relays, contacts, and the like, associated with the various blocks, are the same, these devices and parts thereof 80 will be given the same reference characters, 85 with distinctive exponents added.

70 Referring to Fig. 1, the track rails 1 and 2 of the railroad track are divided into blocks by insulating joints 3 in the usual and well known manner, the length of these 90 blocks being, of course, selected to conform with the braking distances of the trains traveling over the track. Each of these blocks is provided with the usual and well known normally closed track circuit, comprising a track battery 4 and a track relay 5. The usual fixed signals S, ordinarily employed in block signal systems, are shown conventionally; and for simplicity, the controlling circuits for these signals have not 95 been shown.

80 Associated with each block is a trackway element T, the function of which is to transmit controlling impulses to passing trains, depending upon traffic conditions in 100 the next block in advance. The trackway element T illustrated is of the inductive type, and comprises (see Fig. 4) two side members 6-6, shown as angular in cross-section, which extend along the track 110

parallel with the track rails 1 and 2 for a distance suitable for obtaining the desired duration of impulse; a cross-connecting core 7; and a coil 8 on said core. In accordance 5 with this invention it is contemplated that the trackway element T will cooperate with a car carried element and associated control devices of the type requiring the coil 8 of the trackway element T to be energized for 10 clear traffic conditions, and to be deenergized under dangerous traffic conditions.

The desired control of the coil 8 of the trackway element T of each block is obtained by any one of the three arrangements 15 shown in Figs. 1, 2 and 3, the primary purpose of these various arrangements being to cut in the supply of current to said coil 8 only upon the approach or during the 20 passage of a train. In each modification the controlling circuit for energizing the coil 8 of the trackway element T is made dependent upon traffic conditions in the block next in advance through the medium of the line relay L, which has a controlling 25 circuit including a front contact of the track relay of the block next in advance.

Referring to Fig. 1, the energizing circuit for the coil 8 of the trackway element T may be traced as follows: commencing at one 30 terminal of the coil 8, conductor 9, back contact of track relay 5, conductor 10, front contact of line relay L, conductor 11, track battery 12, conductor 13 and back to the other terminal of said coil. As the train 35 enters each block, it shunts out the track relay 5 of that block, and if the next block in advance is not occupied, the front contact of the line relay L is closed, so that the 40 circuit for energizing coil 8 of the trackway element in question is established. In this arrangement, the trackway element T of each block is located in advance of the insulating joints 3 at the entrance to that block and at a distance therefrom sufficient 45 to permit the shunting of the track relay 5 and to complete energization of the coil 8 before a train traveling at maximum speed reaches the trackway element T. It will 50 be observed that the circuit for energizing the trackway element is normally opened and is closed only upon the approach of a train, and that it is again opened as soon as the train has passed out of the block. In this way, there is no current demand 55 upon the track battery 12 except when required; and since this occurs at comparatively infrequent intervals during the passage of trains, the primary batteries, ordinarily employed in block signal systems, 60 may be utilized for supplying current to the trackway elements of the train control system.

In Fig. 2 the energizing circuit for the coil 8 of each trackway element includes,

in addition to the front contacts of the line relay L, a circuit controller operated by a time element device G. This circuit controller, as illustrated diagrammatically, consists of two resilient contact members 14-14 adapted to be bridged or connected 65 by an insulated contact button or block 15. The contact button 15 is carried by, but insulated from, the core 16 of a solenoid 17. The energizing circuit for the solenoid 17, 70 readily traced on the drawing, includes the back contact of the track relay 5 of the corresponding block. Associated with the core 16 is some form of a time-controlled mechanism adapted to retard the upward 75 movement of said core, so that after the contact block 15 has been moved into contact with the members 14, this electrical connection will be maintained for a predetermined interval of time and then, upon continued movement of said core, will be 80 interrupted. As shown, this time controlled device comprises a dashpot cylinder 18 having a restricted inlet opening 19 in its lower end; and movable in the cylinder 18 is a piston 20 which is connected to the core 85 90 16 and which is provided with a flexible packing, or the like, for preventing the passage of air thereby to the lower end of the cylinder, but permitting free passage of air thereby from the lower end of said 95 cylinder.

In this arrangement shown in Fig. 2, when a train enters a block, it shunts the track relay 5 of that block and energizes the solenoid 17 of the time controlled device G. Immediately after the solenoid 17 is energized, the circuit for energizing the corresponding trackway element T is closed at the contacts 14-14 and the contact block 15, and if the next block in advance is not occupied, so that the line relay L is picked up, a circuit for the coil 8 of said trackway element is completed. In this arrangement, trackway element T is also located in advance of the insulated joints 2 at the entrance to the block a distance sufficient to allow the closing of the back contacts of the track relay, energization of solenoid 17, closing the contacts 14-14 and 15, and full energization of coil 8 of the corresponding trackway element T before a high speed train reaches said trackway element. The time interval, for which the time controlled device G is adjusted, is preferably made as short as possible, the minimum being such that a train, traveling at low speed, will have time enough to pass the trackway element before the contacts of said time-controlled device open. It will be observed that this arrangement provides for cutting in the energy supply for the trackway element T only when a train approaches and is about to pass such trackway element, and

further, that such energy supply is cut off as soon as there has been time for the train to pass said trackway element.

In the arrangement shown in Fig. 3, the energizing circuit for the coil 8 of each trackway element T associated therewith and protecting a particular block includes the front contact of an additional relay 21 connected in series with the track battery 12. 10
10 4 of the block next in the rear. This relay 21 is so constructed and adjusted that it will not pick up upon the current flowing when the track circuit is not occupied, but will pick up when a train enters the track 15 circuit, or when it reaches some intermediate point in the block, on account of the increased flow of current due to the lower resistance of the train shunt. Thus, in this arrangement the energy supplied to the 20 trackway element protecting each block, as the block B, is cut in sometime after the train enters the block next in the rear, as the block A, and is cut off when such train leaves said block in the rear. In this arrangement the trackway element T may be 25 located at any desired point in the rear of the entrance to the block corresponding thereto and which it protects and may be controlled through the front contact of the 30 track relay of that block as well as the track relay of the block next in advance.

Various forms of car carried elements responsive to the trackway elements hereinbefore described, may be employed, and 35 likewise, various types of control devices and automatic train control means governed by said car carried element may be used. The construction of parts and arrangements of circuits illustrated in Fig. 4 is, therefore, 40 merely illustrative of a car equipment suitable for use with the trackway element T. Referring to Fig. 4, the car carried element L comprises a magnetic yoke Y having pole pieces 22. Coils 23 are carried on 45 each leg of the yoke Y, and are connected in series with the battery 24, a check relay 25 and the primary of a transformer 26. The secondary of said transformer 26 is connected in circuit with the windings of a control relay R, preferably of a type responsive to alternating currents. The train control apparatus governed by the check relay 25 and the control relay R may be of any suitable construction, and is shown diagrammatically as an electro-pneumatic 50 valve, E. P. V., adapted to cause an automatic application of the brakes, or control some other suitable means. The circuit for the E. P. V. includes a battery 27, the back contact of a contact finger or armature 28 of the control relay R, and the front contact and armature 29 of the check relay 25.

While the car or train is traveling between signaling points, the current from the battery 24 passes through the coils 23 and mag-

netizes the yoke Y with a polarity, such as indicated in Fig. 4. Under clear traffic conditions, the coil 8 of the trackway element T is energized from the track battery 12, as previously explained; and the arrangement 70 is such that the side members 6-6 of said trackway element have a polarity, as indicated in Fig. 4, opposing the polarity of the pole pieces of the yoke Y on passing cars. Consequently, under clear traffic conditions, 75 when the car passes a trackway element, the reluctance of the magnetic circuit through the yoke Y is not materially altered, at least not enough to cause operation of the relay R. Under dangerous traffic conditions, however, the coil 8 of the trackway element T is open-circuited, so that said trackway element presents in effect a magnetic bridge or loop for the yoke Y on a passing 80 car. Thus, the reluctance of the magnetic circuit through the yoke Y on the passing car is greatly changed, thereby resulting in changing the amount of magnetizing current flowing through the coils 23 and through the primary of the transformer 26. This 85 change in current in the primary of the transformer 26 induces a current in its secondary, thereby picking up the control relay R and deenergizing the E. P. V. or other 90 train control device. The check relay 25 assures the integrity of the circuit for energizing the coils 23; and if this circuit should become broken, or the battery 24 depreciate, the check relay 25 would cease to hold up its 95 armature 29 and would interrupt the circuit 100 for the E. P. V., thus producing an automatic operation of the E. P. V., or other train control device, to signify that the system is out of order. The transformer 26 and the relay R are preferably constructed 105 in a self-contained unit, all of the parts being of a substantial and sturdy construction such that no breaking or failure of parts is likely to occur.

In disclosing my invention, simplified and diagrammatic forms of illustration have been employed, and no attempt has been made to show the exact construction preferably employed in practice. Obviously various modifications may be made in the construction illustrated, and other parts and devices may be added in order to make a more complete system, all without departing from my invention. I desire to have it understood, therefore, that the specific embodiments shown and described are merely illustrative of my invention, and do not exhaust the various modifications and adaptations of the underlying idea of means constituting my invention.

What I claim as new and desire to secure by Letters Patent, is:—

1. In an automatic train control system for railroads having tracks which are divided into blocks each provided with a nor-

normally closed track circuit, the combination with a trackway element associated with each block and located a short distance in advance of the entrance thereof, a time controlled device associated with each trackway element and set into operation by the shunting of the track relay of the corresponding block, said device having normally open contacts and an energizing circuit for said trackway element including a local battery and said normally open contacts, whereby said energizing circuit is automatically closed and then opened by said time controlled device after it has operated for a predetermined time.

2. In an automatic train control system adapted for railroads divided into blocks having normally closed track circuits and of the type in which a normally deenergized track element is located near the entrance to each block and is provided with a normally open circuit for energizing it, a circuit controller for opening and closing a break in said circuit, and electrically operated time controlled means set into operation by the dropping of the track relay of the corresponding block for actuating said circuit controller, said means acting to close the circuit controller quickly, then open it after a predetermined time, and then hold it open so long as the track relay controlling it is dropped.

3. In an automatic train control system of the type specified in claim 2, the combination with the circuit controlling the track element, of automatic time controlled means set into operation by the entrance of a train into the corresponding block for closing a break in said circuit for a short time once while said block is occupied.

4. In an automatic train control system of the type specified in claim 2, the combination with the circuit for controlling the track element, of electrically operable time controlled means set into operation by the entrance of a train into the corresponding block for quickly closing a break in said circuit and then opening the break after a predetermined time, said track element being located a short distance in advance of the entrance to its corresponding block sufficient to allow time for the track relay to drop and the time controlled means to close the circuit before a fast moving train reaches said track element, the time for which said time controlled means is adjusted being substantially as long as that required for a slow moving train to reach the track element.

5. In an automatic train control system of the type specified in claim 2, the combination with the circuit for controlling the track element, of electrically operable means for closing and opening a break in said circuit, said means comprising a movable element, contacts closed during a portion of

the movement of said element, time controlled means for regulating the rate of movement of said element in one direction, and electromagnetic means for moving said element for its entire range of movement. 70

6. In an automatic train control system for railroads having tracks divided into blocks each provided with a normally closed track circuit having a track relay, a track element associated with each block, a circuit 75 for each track element adapted when open to place that element in its active stopping condition, and normally deenergized time controlled means associated with each track element and set into operation by the dropping of the track relay of the corresponding block, said means acting to break said circuit after the lapse of a predetermined interval of time following the initiation of the operation of said means and to maintain such break so long as its controlling track relay is deenergized. 80

7. In an automatic train control system for railroads having tracks divided into blocks each provided with a normally closed track circuit having a track relay, a track element associated with each block, slow acting means adapted when set into operation to place said track element at once in its inactive condition provided the next block 90 in advance is not occupied and to maintain such condition for a predetermined time only, and a controlling circuit for said means governed by the back contact of the track relay of the corresponding block. 100

8. In an automatic train control system for railroads having tracks divided into blocks each provided with a normally closed track circuit, a track element associated with each block and having a coil, said track element assuming its inactive condition when current flows through said coil, slow acting means associated with each track element and adapted when changed to its ultimate condition to interrupt the supply of current to the coil of that track element, and means responsive to the shunting of a track circuit adjacent to the track element for causing the slow acting means to change slowly to its ultimate condition and to remain in that condition so long as that track circuit is shunted. 110 115

9. In an automatic train control system for railroads having tracks divided into blocks each provided with a normally closed track circuit, a track element located at a distance in advance of the insulated joints at the entrance to each block, said track element having a coil which causes the element to assume its inactive condition when current flows in the coil, and time controlled means associated with each track element and set into operation by the shunting of the track circuit of the corresponding block for interrupting the supply of current to the coil 120 125 130

of the track element after a predetermined time and for maintaining such interruption so long as that track circuit is shunted.

10. In an automatic train control system for railroads having tracks divided into blocks each provided with a normally closed track circuit having a track relay, a track element for each block having a coil adapted when supplied with current to place the element in its inactive condition, and slow acting means associated with each track element and set into operation by the dropping of the track relay of the corresponding block for interrupting the supply of current to its coil after a predetermined lapse of time and for continuing such interruption so long as said track relay is deenergized.

11. In an automatic train control system for railroads having tracks divided into blocks each provided with a normally closed track circuit, a track element for each block having a coil adapted when current flows therein to place the element in its inactive condition, slow acting means changeable to an ultimate condition and adapted when in its ultimate condition to interrupt the supply of current to the coil of the corresponding track element, and means controlled by a track circuit adjacent to each track element for causing the slow acting means associated therewith to change to its ultimate condition and to remain in that condition so long as that track circuit is occupied.

12. In a train control system for railroads a track element having a coil, normally deenergized electrically operable slow acting means adapted when energized to change slowly to an ultimate condition and continue in that condition so long as energized, said slow acting means acting in its ultimate condition to interrupt the flow of current to said coil, and energizing circuit for said coil, and means for closing the energizing circuit once during the approach and passage of a train by the track element.

13. In a train control system for railroads having track circuits, the combination with a track element comprising a magnetic core and a coil thereon, a source of current and a circuit for energizing the coil, time controlled means set into operation by a train on a track circuit adjacent to the track element for opening said energizing circuit after a predetermined interval of time and for maintaining that circuit open so long as said adjacent track circuit is occupied.

14. In a train control system for railroads having track circuits with track relays, the combination with a track element including a coil adapted when energized to place the track element in its inactive condition, an energizing circuit for said coil, normally de-energized slow acting circuit controlling means adapted when energized to close a break in said circuit at once and to open

it after a predetermined interval of time, and a control circuit for said slow acting means governed by the back contact of a track relay adjacent to the track element.

15. In a train control system for railroads provided with blocks each having a normally closed track circuit, the combination with the track element adjacent to the entrance to a block and having a coil, an energizing circuit for the coil, time controlled means adapted when operated to close the energizing circuit quickly and after a predetermined interval of time to open that circuit and hold it open, and automatic means for causing operation of the time controlled means when the track circuit of said block is occupied.

16. In a train control system for railroads having blocks provided with track circuits, the combination with a track element near the entrance to a block, an energizing circuit for the track element governed by the track circuit of the block next in advance of said block, and slow acting means operated by the presence of a train in said block for opening the energizing circuit after a predetermined time and for maintaining it open so long as said block is occupied.

17. In a train control system for railroads having blocks provided with track circuits, the combination with a track element associated with a block for governing train movement in that block, said track element having a coil adapted when energized to place the element in its inactive condition, an energizing circuit for the coil, means governed by the track circuit of the block next in advance of said block for governing the energizing circuit, and time controlled means governed by a track circuit adjacent to the track element for independently opening its energizing circuit after a predetermined time and for maintaining it open so long as said adjacent track circuit is occupied.

18. In a train control system for railroads having blocks provided with track circuits, a track element associated with each block, a traffic controlled energizing circuit for each track element, and slow acting means responsive to the shunting action of the wheels and axles of a train adjacent to the track element for independently interrupting its energizing circuit after a time sufficient for the front end of the train to pass the track element and for maintaining interruption of said circuit so long as any part of the train is adjacent to the track element.

19. In a train control system for railroads having blocks, a track element associated with a given block and comprising a magnetic core and a coil thereon, a battery, an energizing circuit for the coil including the battery and having a normally open break therein, and automatic means for closing the break in said circuit upon the approach of a train to the track element and for open-

ing that break after a time, said means maintaining said break open until the train has passed the track element regardless of the length of the train.

- 5 20. In a train control system for railroads having blocks provided with track circuits, a track element located a distance in advance of the entrance to each block, an energizing circuit for each track element, a relay 70 governed by the track circuit of the block next in advance of the corresponding block for controlling said energizing circuit, time controlled means for independently opening the energizing circuit after a predetermined 75 time, and means governed by the track circuit of said corresponding block for operating the time controlled means once only during the passage of a train through that block.
- 10 21. In a train control system for railroads having blocks provided with track circuits and track relays, a track element associated with a block and including a coil adapted when energized to render the element inactive, a local battery, an energizing circuit for the coil including the battery, electrical- 80 ly operable slow acting means adapted when energized to close a break in the energizing circuit and then open it after a predetermined 85 time, said means while energized after a lapse of said time maintaining the circuit open, and a controlling circuit for the slow acting means including a back contact of a track relay adjacent to the track 90 element.
- 15 22. A device for governing the supply of current to the track element of automatic train control systems so as to economize in the energy required for said elements comprising, a biased movable element, circuit 95 controlling means closed when the element is moved part way from its biased position and maintained closed until the element nearly reaches its ultimate position, means 100 for retarding the movement of the element from its biased position but permitting quick return to that position, and electro- 105 responsive means adapted when energized to cause movement of the element from its biased position to its ultimate position.
- 20 23. In a train control system, the combination with a track circuit, a track element having a magnetic core and a coil thereon, a battery, a circuit including the 110 battery and coil, said circuit having a normally open break therein so that no current flows in the coil, and means responsive to the shunting of said track circuit for closing the break in said circuit for a predetermined time only once while said track circuit is shunted.
- 25 24. In a train control system, the combination with two adjacent blocks each having a track circuit, a track element located a 115 distance in advance of the entrance to the 120 rear block, said track element having a coil and being placed in its inactive condition when current flows in the coil, and automatic means governed by both of the track circuits for supplying current to the coil of the track element as soon as a train enters the rear block provided the forward block is not occupied, said means maintaining such supply of current for a limited time only regardless of the length of the train. 125
- 30 25. In a train control system having blocks provided with track circuits, a track element located a distance in advance of the entrance to each block, said track element having a coil and assuming its inactive condition when current flows in the coil, a local battery for each track element, and automatic means effective when a train enters a block to supply current to the corresponding track element from its battery provided the next block in advance is not occupied, said means automatically interrupting such supply of current after a predetermined time sufficient for the front end of the train to pass the track element and also continuing such interruption until the train leaves said corresponding block. 130
- 35 26. In an automatic train control system for railroads having tracks divided into blocks each having a normally closed track circuit and including a normally energized track relay; a track element near the entrance to each block comprising a core of magnetic material having a coil thereon; a circuit for said coil including a normally closed contact controlled by the track relay of the next block in advance; and a time controlled device set into operation by the deenergization of the track relay at the entrance to a block for controlling the circuit for the track element at the entrance to the corresponding block. 135
- 40 27. In an automatic train control system for railroads having tracks divided into blocks each provided with a normally energized track relay, a track element associated with each block and located to affect suitable receiving means on a passing vehicle a short distance after said vehicle enters said block, said track element having a winding and assuming its active stopping condition unless said winding is energized, a source of current and a normally open circuit for energizing said winding; and means includ- 140 ing a time controlled circuit controlling device for closing said energizing circuit and for thereafter opening said energizing circuit after an intervening interval of time, said time controlled device being electrically operated and normally de-energized, and an energizing circuit for said time controlled device including a back contact of the track relay of the corresponding block. 145
- 45 28. In a train control system of the intermittent inductive type for railroads hav- 150

- ing tracks divided into blocks each provided with a normally energized track relay, a track element for each block located a distance in advance of the entrance to that 5 block and adapted to transmit inductively a control influence to a passing vehicle, said track element comprising a core and a coil thereon and assuming its active stopping condition unless said coil is energized, a 10 normally open circuit for controlling the energization of the coil of each track element, and means including a slow acting circuit-controller in said circuit automatically opened an interval of time after 15 energization of the track relay of the corresponding block for first closing said circuit upon the entrance of a train into the corresponding block and for thereafter opening said circuit after an intervening interval of time. 20
29. In an automatic train control system for railroads having tracks divided into blocks, the combination with a track impulse device near the entrance to each block a short distance in advance thereof, said track 25 device assuming its active stopping condition unless energized, a source of current and a normally open circuit on the trackway for energizing each track device, and means controlled by the track relay of the corresponding block for first closing the energizing circuit of said track device after an interval of delay and for thereafter opening said circuit regardless of the length of the train after a further interval of delay. 30
